UNITED STATES PATENT OFFICE.

JOHN LALLY, OF GREAT NECK, NEW YORK.

BUILDING-COLUMN CONNECTION.

Application filed November 21, 1925. Serial No. 70,703.

My invention relates to building column construction and it is my object to produce simple, strong and cheaply made connections between an **H**-section column and the 5 floor beams and which may be either one-, two-, three- or four-way connections, as the nature of the building may demand.

In the drawing Fig. 1 is a plan view, partly in section, showing four-way connections; Fig. 2 a view, partly in section, of the structure of Fig. 1 on the line 2—2 thereof; and Fig. 3, a view, partly in section, of the structure of Fig. 1 on the line 3—3 thereof.

15 The column itself is of rolled or built-up **H**-section and has a web 1 and flanges 2—2' and 3—3'. Superimposed columns may be connected in any desired manner.

Where a floor beam is to be connected to 20 the parallel flanges 2—3 of the **H**-section column the flanges are slotted at 4 and 5. To make the connection a piece of **T**-section rolled steel is cut off, the length equalling the height of the slots and the head of the

25 **T**-section slightly wider than the distance between the slotted flanges of the column. The head 6 of the **T**-section is slipped into the slots 4 and 5 with its web 7 extending beyond the **H**-section column and parallel 30 with the flanges 2 and 3. The head of the **T**-connection may be welded to the slots as indicated on the drawing. The web of the **I**-beam 8, which carries the floor, may then be secured to the web 7 of the **T**-connection by rivets or in any other suitable manner and lies substantially in line with the column.

If floor beams are to be secured to the 40 **H**-column at right angles to the side flanges slots 9 and 10 are cut in the flanges 2' and 3', which slots are preferably located close to the web 1, and a plate 11 is placed through the slots with their ends projecting beyond the column. If desired the plate may be 45 welded to the slots as shown in the drawing.

The webs of the **I**-beams 12 and 13 may then be secured to the projecting ends of the plate 11 and the beams will line practically 50 in line with the column.

If a floor beam is to be connected to the fourth side of the column it is not practical

to further slot the flanges 2' and 3' as they already have the slots 9 and 10 therein. I prefer to rivet or otherwise secure two pieces 55 of angle iron 14 and 15 to the insides of the flanges 2' and 3' with their tops in line thereby forming a bracket for the **I**-beam 16 to rest upon. In this way floor beams may be connected to all four sides of the 60 column with a minimum of material and labor and with the beams all in substantial alignment with the column thereby avoiding eccentric loading.

I claim:—

1. An **H**-section column, the opposed flanges of which are slotted, in combination with a connection engaging said slots and extending beyond the column and adapted to carry a beam.

2. An **H**-section column, the opposed flanges of which are slotted, in combination with a **T**-section connection the head of which engages the flange slots and the web of which extends beyond the column and is 75 adapted to carry a beam.

3. An **H**-section column, the opposed flanges of which are slotted, in combination with a plate extending through said slots and projecting beyond the column, the end 80 of which is adapted to carry a beam.

4. An **H**-section column all the flanges of which are slotted, in combination with a **T**-section connection the head of which engages the slots in opposed flanges and the web of which extends beyond the column and adapted to carry a beam and a plate extending through the slots in the other flanges and projecting beyond the column, the end of which is adapted to carry a beam. 90

5. An **H**-section column the opposed flanges of which are slotted, in combination with a connection engaging said slots and projecting beyond the column and adapted to carry a beam and a bracket secured to 95 the inside of said slotted flanges and adapted to carry a beam.

6. Building construction comprising an **H**-column, angle brackets secured to the opposed inner faces of two of the flanges and 100 adapted to carry a beam.

In testimony whereof I have affixed my signature.

JOHN LALLY.
